CLAIM

The ornamental design for a kit for converting a van into a camper, as shown and described.

DESCRIPTION

FIG. 1 is a perspective view of the kit for converting a van into a camper, according to the first embodiment; FIG. 2 is a top view of the kit for converting a van into a camper, according to the first embodiment;

FIG. 3 is a bottom view of the kit for converting a van into a camper, according to the first embodiment;

FIG. 4 is a right side view of the kit for converting a van into a camper, according to the first embodiment;

FIG. 5 is a left side view of the kit for converting a van into a camper, according to the first embodiment;

FIG. 6 is a front view of the kit for converting a van into a camper, according to the first embodiment;

FIG. 7 is a rear view of the kit for converting a van into a camper, according to the first embodiment;

FIG. 8 is an exploded perspective view of the kit for converting a van into a camper, according to the first embodiment, showing the kit with components in an open position;

FIG. 9 is an exploded top view of the kit for converting a van into a camper, according to the first embodiment, showing the kit with components in an open position;

FIG. 10 is an exploded bottom view of the kit for converting a van into a camper, according to the first embodiment, showing the kit with components in an open position;

FIG. 11 is an exploded right side view of the kit for converting a van into a camper, according to the first embodiment, showing the kit with components in an open position;

FIG. 12 is an exploded left side view of the kit for converting a van into a camper, according to the first embodiment, showing the kit with components in an open position;

FIG. 13 is an exploded front view of the kit for converting a van into a camper, according to the first embodiment, showing the kit with components in an open position; and,

FIG. 14 is an exploded rear view of the kit for converting a van into a camper, according to the first embodiment, showing the kit with components in an open position.

The broken lines illustrate environment of the article and form no part of the claimed design.
